Patented June 7, 1904.

UNITED STATES PATENT OFFICE.

CARL G. LUNDIN, OF BROOKLYN, NEW YORK.

AUTOMATIC FEEDER.

SPECIFICATION forming part of Letters Patent No. 761,689, dated June 7, 1904.

Application filed December 10, 1903. Serial No. 184,518. (No model.)

To all whom it may concern:

Be it known that I, CARL G. LUNDIN, a subject of the King of Sweden and Norway, residing at Brooklyn, in the county of Kings and State of New York, have invented certain new and useful Improvements in Automatic Feeders, of which the following is a specification.

This invention relates to improvements in an apparatus to be used for automatically supplying material of various kinds in suitable quantities, and while I have shown it as being used in connection with an acetylene-gas generator for feeding carbid thereto, yet it is applicable for use in feeding grain to spouts or chutes or weighing-machines, or it may be used for various other purposes; and it consists in certain peculiarities of the construction, novel arrangement, and operation of the parts thereof, as will be hereinabove more fully set forth and specifically claimed.

The principal object of the invention is to provide a feeder of the above-named character which may be automatic in its operation and shall be simple and inexpensive in its construction, strong, durable, and so made that when a sufficient quantity of the material shall have passed into the dumping-bucket the same will be dumped, so as to discharge the material, in which operation the supply is shut off until another charge is desired.

Other objects and advantages of the invention will be disclosed in the subjoined description and explanation.

In order to enable others skilled in the art to which my invention pertains to make and use the same, I will now proceed to describe it, referring to the accompanying drawings, in which—

Figure 1 is a vertical sectional view, partly in elevation, of an acetylene-gas generator with my feeder shown in connection therewith. Fig. 2 is a detached view, in side elevation, of the feeder, showing the parts arranged in position for supplying material to the dumping or discharging bucket or vessel. Fig. 3 is a vertical sectional view thereof, showing by dotted lines the position the parts will assume when discharging. Fig. 4 is a front view in elevation showing the position

of the parts when the dumping vessel is in the act of discharging. Fig. 5 is a fragmental view, partly in section and partly in elevation, of a portion of the support and supply-chute, showing the check in position to shut off the supply of material.

Like numerals of reference refer to corresponding parts throughout the different views of the drawings.

The reference-numeral 10 represents the tank of an acetylene-generator, which may be made of any suitable form or material, but preferably cylindrical. Within this vessel is movably fitted a gasometer 11, which is vertically guided by means of a support 12, secured to the upper portion of the cylinder 10 or said tank. The lower portion of the tank 10 is provided with an inclined floor 13, which, together with the horizontal partition 14, forms a compartment for the reception of a quantity of water 15, in which the carbide is discharged through a chute 16, communicating with said compartment and extending upwardly on the outside of the tank. The lower portion of the compartment formed by the floor 13 and partition 14 is provided with a faucet 17, by means of which the water may be withdrawn from said compartment. The central portion of the partition 14 is provided with an inverted funnel 18, the upper end of which is provided with a series of openings 19 to permit of the escape of gas generated by the action of the water on the carbide in the lower compartment. The upper end of the funnel 18 is closed by means of a cap 20, which is usually cylindrical in shape, and is provided in its lower portion with a series of openings 21 to permit of the discharge of the gas. Within that part of the tank 10 above the partition 14 is a quantity of water 15, which submerges the lower portion of the cap 20, so that when the gas passes through the openings 21 it will also pass through a portion of the water and be washed thereby. As the gas rises from the water it will fill the space between the top of the gasometer 11 and the upper surface of the water and by its expansive force will cause the gasometer to rise on its support. Located on the outer surface of the tank 10 above the

upper end of the chute 16 is a carbid-receptacle 22, the lower end of which communicates with and supports the supply chute or conduit 23 of the feeder, which may be provided at 5 its upper end with a hopper 24 to receive the material. This chute or conduit is provided on each of its sides with a depending supporting-arm 25, for the lower portion of the discharging or dumping bucket, which is pivotally secured therebetween. Pivotally secured to the lower portion of the sides of the chute 23 is a check or check-valve, which comprises a bottom or main portion 26, having at each 10 of its side edges a forwardly-extending side 27, between which the supply-chute 23 is located. The front or discharging end of the check is bent to form a downward extension 28, which overlaps the rear portion of the dumping or discharge bucket, as will be clearly 15 seen by reference to Fig. 3 of the drawings. Secured transversely on the bottom 26 of the check-valve is a rod 29, the ends of which project slightly beyond the sides 27 and engage slotted arms 30, one of which is secured to 20 each side of the dumping or discharging bucket. These arms are slightly curved, as shown, so as to permit of the easy operation of the rod or shaft 29 in the movements of the check-valve and dumping-bucket. This 25 bucket 31 is a substantially rectangular-shaped vessel having its upper and front portions open and is pivotally secured at its rear lower corner on a rod or shaft 32, extending across and uniting the lower ends of the supports 25, 30 the upper ends of which are secured to the supply chute or conduit 23, as is clearly shown in Fig. 4 of the drawings. Extending outwardly and upwardly from the upper portion 35 of each of the sides of the bucket 31 is an arm 33, to which is pivotally secured a door 34, used for closing and opening the front portion of said bucket. Pivotally secured to the front lower portion of the bucket 31 is a bail 35, to the upper middle portion of which is loosely 40 connected at one of its ends a rod 36, the other end of which may pass through the floor or a platform (not shown) or may be otherwise 45 suitably supported, so that it can be raised by hand, if desired.

50 In Fig. 1 of the drawings I have shown the rod 36 as passing through the floor 37 of a box-like casing 38, mounted on the upper end of the chute 16, and also as passing through a projection 39 on the carbid-receptacle 22.

55 In this figure the rod 36 is shown as having at its upper end a lateral projection 40 to en-

gage a lug 41 on a bar 42, which is pivotally connected at its upper end to one end of a lever 43, which is fulcrumed on the upper portion of the support 12 and connected at its other end by means of a rod 44 to the top of the gasometer. The lower end of the bar 42 is provided with an enlargement 45, which increases in size toward its bottom. Extending horizontally across the casing 38 is a rod 46, with which the enlargement 45 on the bar 42 will contact in its movements, so as to disengage the lug 41 from the projection 40 when the bar is in its raised position.

As shown by dotted lines in Fig. 1, the dumping-bucket 31 has been tilted and emptied of its contents, so that the carbid discharged therefrom will pass into the lower compartment of the generator, thus causing the generation of gas, which passes through the funnel 18 into the gasometer 11, so as to raise the same to the position shown by continuous lines in said figure, in which operation the enlarged end 45 of the bar 42 will be lowered, so as to bring the lug 41 in position to engage the projection 40 on the rod 36, thereby raising the bucket 31 and the check-valve, so that the latter will shut off the supply of carbid. When the gasometer is further raised, it is evident that the bar 42 will be thrown out of engagement with the projection 40, thus allowing the bucket 31 to turn on its pivot and again discharge its contents.

In using my feeder for discharging grain, coal, or other material substantially the same operation as above set forth is performed, and it is apparent that the dumping-bucket may be operated through the medium of the rod 36 and bail 35 and by hand, if desired.

Having thus fully described my invention, what I claim as new, and desire to secure by Letters Patent, is—

The combination with a supply chute or conduit, of a check-valve embracing and extending under the lower portion of the chute and pivotally supported, a dumping-bucket pivotally supported below said valve and communicating therewith, a slotted arm on each side of the bucket in loose engagement with the valve, and means connected to the front of the bucket to raise and lower the same, substantially as described.

CARL G. LUNDIN.
